BINARY TO DECIMAL TRANSLATOR

Wesley E. Stupar, Burbank, Calif., assignor to General Precision, Inc., a corporation of Delaware

Filed Jan. 5, 1960, Ser. No. 596

2 Claims. (Cl. 340—347)

This invention relates to translators and, more particularly, to a translator for converting information received in one digital code to information in another digital code.

In many applications, such as at the output of a digital computer, it is often necessary to convert the digital representation of the computed results from one digital code to another. The computer, for example, may utilize a binary digital notation whereas output apparatus, such as a printer controlled by the computer, may require a decimal digital input. Depending, therefore, upon the circumstances, one digital code may be more appropriate for a particular function than a second digital code so that a translator for converting is required to convert between the first and second digital codes.

Prior translators for converting digital information from binary to decimal notation utilize a fairly complex arrangement of logical circuit elements such as "and" gates, "or" gates, relays, vacuum tubes and the like. In an illustrative embodiment of this invention, a relatively inexpensive, simple and reliable translator is provided which generates a count pulse for each decimal digit without the use of any logical circuit elements, and with a minimum of output circuitry the translator may be used with a decade counter to register the decimal information periodically or operate as a totalizer or integrator.

In an illustrative embodiment of this invention, binary digital signals are translated to decimal signals by utilizing a coded commutator disc which is engaged by a rotatable contact member. The commutator disc is divided into a number of angular sectors or zones, each of which is utilized for translating a particular binary digit of the input binary information. The angular sectors are divided into a number of concentric tracks which correspond individually to the decimal output digits.

The tracks are individually engaged by brushes which are supported by the rotatable contact member. As the brushes are rotated along the concentric tracks, they successively contact conductive strips which are radially positioned in the tracks in each of the angular sectors. In each of the angular sectors, the conductive strips form with their associated brushes switching conductive members which are electrically isolated from the conductive members in the other angular sectors. The number of conductive strips contacted by each of the brushes during the movement of the brush across a digital angular sector depends upon the significance of the particular binary digit associated with that sector.

The radial conductive strips in the digital angular sectors are energized in accordance with the input binary information. As the brushes are rotated adjacent to an energized strip, a count pulse is generated which is supplied to a decade counter. The significance of the decimal digit for which the generated pulse is counted is dependent upon the radial position of the concentric track and of the brush which generates the pulse. For example, if the radial conductive strips of the angular sector associated with the binary digit representing 2^2 are energized by the binary signals, four pulses are provided for the least significant decimal digit. The reason is that the decimal value of 2^2 is "4."

The coded disc also includes a number of continuous conductive tracks which correspond individually to the output decimal digits and from which the generated decimal pulses are supplied to a decade counter. A brush

2

is provided on the rotatable contact member for each of these tracks as well as for the coded tracks. The brushes contacting the coded tracks are individually connected to the brushes contacting a continuous track so that, as the contact member is rotated, connections are successively established at the strips in accordance with the binary input information to generate a number of pulses which indicates the information in decimal form.

The conductive strips in the tracks are staggered so that two pulses of different decimal significance are not simultaneously generated. The avoidance of the simultaneous generation of two different significant pulses prevents confusion with a carry pulse in the decade counter.

Other features of this invention relate to the provision of two similar coded tracks in each of the digital angular sectors for each of the decimal digits. The two tracks are also angularly displaced from each other so that two successive pulses are generated for each count in the decimal notation as the brushes are rotated. The two successive pulses are utilized to set a flip-flop circuit to the true state and then reset the flip-flop circuit to the false state. The flip-flop circuit in turn steps an individually associated stage of the decade counter to increase the count in the stage by a decimal integer every time that the flip-flop circuit becomes reset to the false condition. Utilization of two pulses for each count eliminates spurious operation of the flip-flop circuit and the counter stage as a result of cracks or other discontinuities on the commutator disc.

Still other features of this invention relate to the provision of a ready signal at the completion of each translation from a binary to a decimal indication. The ready signal is connected to output apparatus which reads the decimal information registered in the decade counter. When the output apparatus has received the decimal information, it enables the translator to reset the decade counter and proceed to translate the next binary indication. The decade counter may be operated as a totalizer or integrator by not resetting it after each translation.

Further advantages and features will become apparent upon consideration of the following description when read in conjunction with the drawings.

In the drawings:

FIGURE 1 is a functional representation of a binary-to-decimal translator embodying this invention;

FIGURE 2 is a sectional view on the line 2—2 of FIGURE 4 and illustrates the commutator disc utilized in a translator embodying this invention;

FIGURE 3 is a sectional view on the line 3—3 of FIGURE 4 and illustrates the brush arrangement of the rotatable contact member utilized in a translator embodying this invention;

FIGURE 4 is a sectional view on the line 4—4 of FIGURE 2 and illustrates the relative positioning of the commutator disc and rotating contact member utilized in a translator embodying this invention; and

FIGURE 5 is a partial plan view of the commutator disc shown in FIGURE 2 with the brushes of the contact member shown in full lines and the circuitry in phantom lines to illustrate their relative positioning in the translator of this invention.

Referring first to FIGURE 1, an input apparatus 12 provides digital signals to an information member or coded commutator disc 10, the details of which are shown in FIGURE 2. The binary signals may be in the form of direct potentials with, for example, the leads $A2^0$ through $A2^n$ being selectively energized by +6 volt potentials. If the binary number which is being supplied by the input apparatus 12 is, for example, the ten digit number 1100001101 where the least significant digit is at the right, the leads $A2^9$ and $A2^8$, $A2^7$, $A2^6$ and $A2^5$ are at a po-

tential of +6 volts with the rest of the input leads A_{2⁷}, A_{2⁶}, A_{2⁵}, A_{2⁴} and A_{2¹} being at zero or ground potential. The commutator disc 10, shown in FIGURE 2, has a maximum input of 10 binary digits but, as indicated above, any number of binary digits may be utilized where the number of digits is either more or less than 10.

When only ten input binary digits are provided, the input leads A_{2⁰} through A_{2⁹} are connected respectively to the ten eyelets B_{2⁰} through B_{2⁹} which, as shown in FIGURE 2, are part of the commutator disc 10. The coded commutator disc 10 is supported on a plate 13 by a number of screws 50 and spacers 51, shown in FIGURE 4. The plate 13 is attached by means of a number of screws 15 to a housing 14 which, together with the plate 13, encloses the commutator disc 10 and a rotating brush block assembly or contact member 11. The contact member 11 is attached by means of a bushing 19 to a shaft 18 that is rotatably supported by two bearings 16 and 17. The bearings 16 and 17 are respectively attached to the housing 14 and the plate 13. As shown in FIGURE 4, the shaft 18 which is concentric with the coded disc 10, rotates the brush block assembly or contact member 11 in a plane which is parallel to the plane of the disc 10. During one revolution of the brush block 11, the input binary signals on the leads A_{2⁰} through A_{2⁹} are converted to digital signals which are supplied to a decimal or decade counter 90 as shown in FIGURE 1.

Referring now specifically to FIGURE 2 which illustrates the coding of the disc 10, the eyelets B_{2⁰} through B_{2⁹} would be respectively connected to the input leads A_{2⁰} through A_{2⁹} of FIGURE 1 and are angularly spaced about the disc 10. The disc or commutator 10 may be considered to be divided into ten angular code zones or sectors C_{2⁰} through C_{2⁹} which correspond to the ten input binary digits. Each of the angular code zones C_{2⁰} through C_{2⁹} contains a code area in the form of a conductive pattern which consists of a number of conductive strips 60, as shown. The strips 60 actually consist of single continuous conductive thin lines.

In addition to considering the disc 10 as being divided angularly into a number of zones, the disc 10 is also divided into six concentric tracks 30 through 35. Each pair of tracks is associated with a decimal digit of particular significance, with the tracks 30 and 31 being associated with the least significant decimal digit 10⁰ or units, the tracks 32 and 33 being associated with the next significant decimal digit 10¹ or tens, and the tracks 34 and 35 being associated with the decimal digit 10² or hundreds.

In zone C_{2⁰}, the strip in track 30 is one single line as is the strip in track 31 and these strips are electrically connected together. In zones C_{2¹} through C_{2⁹}, the strips are actually rectangular loops of interconnected metallic conductive material. However, the tracks 32 and 33 in zone C_{2⁴} and tracks 34 and 35 in zone C_{2⁷} are identical to the strips in tracks 30 and 31 in zone C_{2⁰}. For example, in the angular zone C_{2¹}, the eyelet B_{2¹} is conductively coupled to the strips 60 which form two squares in zone C_{2¹}. The conductive strips 60 in each of the zones C_{2⁰} through C_{2⁹} are at the same potential as the associated one of the eyelets B_{2⁰} through B_{2⁹} and, therefore, the associated one of the input leads A_{2⁰} through A_{2⁹}. In the above example, with the binary input number being 1100001101 where the least significant digit is at the right, the conductive strips 60 in the conductive zones C_{2⁰}, C_{2²}, C_{2³}, C_{2⁸} and C_{2⁹} are at +6 volts, and the conductive strips 60 in the conductive zones C_{2¹}, C_{2⁴}, C_{2⁵}, C_{2⁶} and C_{2⁷} are at zero volts.

The ten angular zones do not occupy equal sectors about the disc 10 nor do they occupy sectors the angles of which are related to each other by any simple arithmetic or geometric progression. The angular length of each of the zones C_{2⁰} through C_{2⁹} depends upon the particular coding for the associated digit to translate the digit into

75 a number of radial strips 60 which will indicate, in decimal form, the same number.

The contact member 11, which as indicated above rotates adjacent to the coded disc 10, supports fourteen brushes 71 through 84. The brushes 71 through 76 engage, respectively, the tracks 30 through 35, and the brushes 77 through 84 contact the concentric tracks 40 through 48 which are hereinafter described. As the brushes 71 through 76 are rotated along the associated tracks 30 through 35, they contact in each of the zones C_{2⁰} through C_{2⁹} a particular number of radial strips 60 depending upon the coding of the strips 60 for the particular binary digit.

For example, in the zone C_{2⁵}, as illustrated particularly in FIGURES 2 and 5 by an arrow, the brushes 71 and 72 may be rotated in a clockwise direction with respect to the disc 10. As each brush rotates, it contacts two radial strips which are on opposite sides of two small squares respectively located in the tracks 30 and 31. If the strips 60 in zone C_{2⁵} are energized, that is, at a potential of +6 volts, two pulses are generated through each of the brushes 71 and 72 as they pass across the radial strips 60 of the zone C_{2⁵}.

25 The particular coding in each of the zones C_{2⁰} through C_{2⁹} is to provide a number of pulses for each of the three decimal digits 10⁰, 10¹ and 10² which together indicate in decimal form the input binary number. The following table illustrates the coding:

Binary Digit	Decimal Equivalent	Generated Pulses		
		10 ²	10 ¹	10 ⁰
2 ⁰	1			1
2 ¹	2			2
2 ²	4			4
2 ³	8			8
2 ⁴	16		1	6
2 ⁵	32		3	2
2 ⁶	64		6	4
2 ⁷	128	1	2	8
2 ⁸	256	2	5	6
2 ⁹	512	5	1	2

To translate, for example, the binary digit 2⁵, it is necessary to provide two pulses for the 10⁰ digit and three pulses for the 10¹ digit because 2⁵ is equal to 32 in decimal notation. The coding of the strips 60 in the zone C_{2⁵}, as shown in FIGURES 1, 3 and 6 provide for this conversion as the brushes 71 and 74 are rotated along the tracks 30 and 33 in the zone C_{2⁵}.

50 Considering briefly, another illustration of the coding before proceeding with the description of the rest of the disc 10, the coding in the angular zone C_{2⁷} provides eight pulses in each of the tracks 30 and 31, two pulses in each of the tracks 32 and 33 and a single pulse in tracks 34 and 35 as the brushes 71 through 76 pass respectively along these tracks.

55 As shown in FIGURE 3, the brushes 71 through 76 are each electrically connected to another one of the brushes (77 through 82) which is also supported by the contact member 11. The brushes 77 through 82 contact respectively six substantially continuous output decimal tracks or rings 40, 44, 41, 45, 42 and 43 which are connected respectively to the output eyelets 20, 28, 21, 27, 22 and 23. As the brushes 71 through 82 are rotated along the tracks 30 through 36 and 40 through 45, the strips 60 in the zones C_{2⁰} through C_{2⁹} are successively engaged so that those which are energized provide for a pulse through a pair of brushes and one of the rings 40 through 45 to its associated eyelet.

70 For example, with the input binary number being 1100001101, as the brush 71 passes along track 30, it engages in zone C_{2⁰} one energized radial strip 60 to generate one pulse through the brush 71, the brush 77, and the ring 40 to the output eyelet 20. As is described hereafter, the output eyelet 20 is coupled to the first or least

significant state **90a** of the decade counter **90**. In the zone **C2⁰**, radial conductive strips **60** are provided only for the least significant decimal digit **10⁰** so that pulses are generated only for the least significant stage **90a** of the counter **90**.

In the input binary number, the second least significant digit is zero so that the strips **60** in the zones **C2¹** are not energized and pulses are therefore not generated when the brushes **71** through **76** pass along the tracks **30** through **35** across the zone **C2¹**. The value of the next significant binary digit **C2²**, however, is a "1" in the example expressed above so that the conductive strips in the zone **C2²** are energized. In zone **C2²**, each of the tracks **30** and **31** includes four radial conductive strips **60** so that four pulses are generated through brush **71** and through brush **72** as the brushes **71** and **72** pass across the angular zone **C2²**.

The translating sequence continues in this manner as the brushes **71** through **82** are rotated around the disc **10**. In each of the energized zones **C2⁰** through **C2⁹**, a particular number of pulses are generated for each of the three significant decimal digits so as to indicate, in decimal form, the input binary information.

As will be discussed in detail subsequently, the tracks **30** and **31** are similar to each other; the tracks **32** and **33** are similar to each other; and the tracks **34** and **35** are similar to each other. The tracks in each pair are actually angularly displaced from each other by a small angle, as best shown in FIGURE 2, so that each pulse generated from the outside track of each pair of tracks is always immediately followed by a second pulse from the inside track of said pair. This action resets the flip-flops **91**, **92** and **93** preparatory to actuate the counter **90** on the next pulse.

As shown in FIGURE 2, the leads **20a**, **21a**, **22a**, **23a**, **27a** and **28a** are connected respectively to the eyelets **20** through **23**, **28** and **27**, and are also connected to three flip-flop circuits **91** through **93**. More specifically, the leads **20a**, **22a** and **28a** are connected respectively to the set terminals of the flip-flop circuits **91** through **93** and the leads **21a**, **23a** and **27a** are connected respectively to the reset terminals of the flip-flop circuits **91** through **93**, as shown in FIGURE 1.

Each of the flip-flop circuits **91** through **93** is a bistable circuit having two equilibrium conditions referred to as "set" and "reset" conditions. The "set" condition corresponds to the true state of the flip-flop and the "reset" condition corresponds to the false state of the flip-flop. A positive pulse at the set terminal causes the flip-flop circuit to become set to its true condition and a positive pulse at its reset terminal causes the flip-flop to become reset to its false condition.

As will be seen from the arrows in FIGURES 2, 3 and 5, when the brushes are rotated clockwise, the pulses generated from the track **30** lead the pulses generated from the track **31** because of the small angular displacement described above for these two tracks. For each pair of associated pulses from the two tracks **30** and **31**, the first pulse passes through lead **20a** to set the flip-flop circuit **91** to the true state, and the second pulse passes through lead **21a** to reset the circuit **91** to the false state. In a similar manner, the pulses generated from the tracks **32** and **33** respectively set the flip-flop circuit **92** to the true state and reset the flip-flop to the false state. Similarly, the pulses generated from the tracks **34** and **35** respectively set the flip-flop circuit **93** to the true state and reset the flip-flop to the false state.

As the brushes **71** through **82** are rotated, therefore, the flip-flop circuits **91**, **92** and **93** are set to the true state and reset to the false state for each decimal count or indication from the commutator disc **10**. A stepping pulse for the counter **90** is provided by the flip-flop circuits when they are reset to their false conditions. Since the circuits **91** through **93** are connected respectively to the stages **90a** through **90c** of the counter **90**, the stages **90a**

through **90c** of the counter become, therefore, respectively stepped when the associated flip-flop circuits are reset to their false conditions.

The double coded tracks for each decimal digit eliminate false operation due to discontinuities or dirt on the commutator disc **10** and provide a continuous check of the accuracy on the translation. For example, if the flip-flop circuit **91** is set by a spurious signal, it remains set until a pair of count pulses from the tracks **30** and **31** are supplied as set and reset pulses to the circuit. The first or set pulse does not change the condition of the circuit **91** and the reset pulse causes it to trigger back to its false condition. When the circuit **91** resets, it provides a count pulse to the counter stage **90a**. During the time the flip-flop circuit is set to its true condition, a count pulse is not provided to the stage **90a** so that the spurious signal which sets the circuit **91** does not destroy the translating accuracy.

The stages **90a** through **90c** of the counter **90** are serially connected so that when a count of **10** is reached by any stage, a carry or count pulse is provided to the next significant or adjacent stage. For example, the tenth pulse from the flip-flop circuit **91** to the stage **90a** sets it to register "0" and causes it to provide a carry pulse of "1" to the stage **90b** to increase the count in the stage **90b** by an integer.

As indicated in FIGURE 1, the counter **90** may include any number of serially connected stages depending upon the number of input binary digits and what type of output information is required. The output information may either be a decimal indication of each binary input number with the counter **90** being reset after each translation, or the information may be a decimal indication of the accumulation or sum of a number of binary input numbers. If the latter, a larger number of counter stages is utilized. Before describing the operation of the translator to provide these two types of output information, the operation of the translator and, in particular, the stages **90a** through **90c** of the counter **90** are briefly described for the binary input number **1100001101** mentioned as an example above.

For the input number **1100001101**, the strips **60** in the zones **C2⁰**, **C2²**, **C2³**, **C2⁸** and **C2⁹** are energized at a potential of +6 volts, and the strips **60** in the rest of the zones are at ground potential. As the contact member **11** rotates in a clockwise direction when viewed from FIGURE 2, the brushes **71** through **76** successively contact the energized strips **60** in the zones **C2⁰**, **C2²**, **C2³**, **C2⁸** and **C2⁹** to generate pulses for introduction to the flip-flop circuits **91** through **93**. The contact member **11** is rotated at a relatively high speed which may be 1000 revolutions per minute so that the pulses to the circuits **91** through **93** are brief. At 1000 revolutions per minute, the contact member **11** completes a revolution in 60 milliseconds, the spacing between the radial strips **60** in each of the tracks **30** through **35** provide for an inter-pulse interval of approximately 0.6 millisecond. The width of the radial strips **60** provides for a duration of approximately 0.06 millisecond in the pulses introduced to the flip-flop circuits **91** through **93**.

For the binary input number **1100001101**, when the contact member rotates across the zones **C2⁰**, a 0.06 millisecond pulse is produced first to set the circuit **91** to the true state and then a reset pulse is produced to reset the flip-flop circuit **91** to the false state. The spacing between pulses from any track as indicated above is 0.6 millisecond but, because the track **31** is staggered with respect to the track **30**, the reset pulse follows the set pulse by the smaller interval of 0.3 millisecond.

After the member **11** has passed the zone **C2⁰**, the counter stages **90a**, **90b** and **90c** register respectively 1, 0 and 0. The strips **60** in the zone **C2¹** are not energized so that the registration of the counter **90** does not change as the contact member **11** passes through the zone **C2¹**. The following table illustrates the registration in the

stages 90a, 90b and 90c during each successive step of the translation of the binary number 1100001101 as the contact member 11 rotates along the disc 10:

Input	Zone	Number of Pulses to—			Registration		
		90c	90b	90a	90c	90b	90a
1	C2 ⁰	0	0	1	0	0	1
0	C2 ¹	0	0	0	0	0	1
1	C2 ²	0	0	4	0	0	5
1	C2 ³	0	0	8	0	1	3
0	C2 ⁴	0	0	0	0	1	3
0	C2 ⁵	0	0	0	0	1	3
0	C2 ⁶	0	0	0	0	1	3
0	C2 ⁷	0	0	0	0	1	3
1	C2 ⁸	2	5	6	2	6	9
1	C2 ⁹	5	1	2	7	8	1

The decimal equivalent of the binary number 1100001101 is 781 which are the digits registered respectively in the stages 90c, 90b and 90a of the counter 90 when the translation is complete.

During the time the contact member 11 is rotating adjacent zone C2⁸, which is energized in the example given above, the first pulse to the stage 90a causes the stage 90a to register 0 and to produce a carry pulse for introduction to the stage 90b. If the pulses from the flip-flop circuit 92 coincide in time with the carry pulses from the stage 90a, only a single count will be registered each time instead of two. It is necessary, therefrom, that the pulses from the circuits 92 and 93 are not synchronized with the respective carry pulses. The desynchronization is provided by staggering each pair of tracks with respect to the other two pairs of tracks. As shown in FIGURE 2, the three pairs of tracks 30-31, 32-33 and 34-35 are staggered so that the pulses from different tracks can never occur at the same time. Actually it is the pulses from the three tracks 31, 33 and 35 which provide the reset pulses that must be staggered since a count pulse is provided when the flip-flop circuits 91 through 93 become reset to the false state.

Toward the end of one rotation of the contact member 11, the brushes 83 and 84, which are electrically connected, contact respectively two relatively short tracks 46 and 47. The tracks 46 and 47 are concentric with the coded tracks 30 through 35 and the substantially continuous rings or tracks 41 through 45. When the brushes 83 and 84 contact the tracks 46 and 47, a path is completed from a potential source 25b, shown in FIGURE 1, through the lead 25a connected to the eyelet 25 in FIGURE 2, track 47, brush 84, brush 83, eyelet 26 and lead 26a to the output apparatus 95.

The signal introduced from the source 25b to the output apparatus 95 functions as a ready or start signal to the apparatus 95 to indicate that the translation stored in the counter 90 is completed. The apparatus 95, which may be a printer or other read-out equipment, thereupon reads the decimal indication stored in the counter 90 and applies an enabling signal to the input apparatus 12 to indicate the reading operation is complete.

The operation of the output apparatus 95 is quite rapid so that by the time the brush 83 leaves the short track 46, the read-out sequence is completed. After leaving the track 46, the brush 83 contacts another track 48 which is at the same radial distance as the track 46. When the brush 83 contacts the track 48, it completes a path for resetting the counter 90 to a decimal value of "0" so as to prepare the counter for the next translating sequence. The reset path is from the potential source 25b in FIGURE 1 to lead 25a, eyelet 25, track 47, brush 84, brush 83, track 48, eyelet 24, lead 24a and a switch 100 to the stages 90a through 90c of the counter 90.

The switch 100 may be set in any one of three positions 1 through 3. When set in position 1, it completes the path for the reset pulse from the commutator disc

10 to the counter 90 so that the counter 90 is automatically reset after each translation. If the switch 100 is set at its second position, the reset path is open and the counter 90 is not automatically reset. The next translation pro-

5 vides count pulses to the stages 90a, 90b, 90c, etc., which are added to the previous registration. This step in effect programs the translator to function as an integrator. The counter 90 functions, therefore, as an integrator when the switch 100 is set at its second position to provide a 10 cumulative count of the sum of the translated numbers. The third position of the switch 100 is a manual-reset position as it connects a potential source 99 to reset the counter 15 stages 90a, 90b, etc., to a value of "0."

As described above when the apparatus 95 reads the 20 registered decimal number, it introduces an enabling signal to the input apparatus 12. The enabling signal from the output apparatus 95 is introduced to a bank of enabling gates 12A in the input apparatus 12 to open the gates for the introduction of a new binary indication through

25 the gates to the different input terminals of the commutator disc 10. The enabling signal indicates that the read-out sequence is completed so that the next binary number can be supplied through the leads A2⁰ through A2⁹ to the commutator disc 10. Actually, the enabling signal is

30 only to insure the successive operation of the translator and the output apparatus. This interaction is referred to an interlocking the output apparatus 95 with the translator because the output apparatus 95 does not operate until it receives a signal from the translator at the end 35 of a translating sequence and the translator cannot operate unless it receives an enabling signal from the apparatus 95 at the end of a read-out sequence.

Although this application has been disclosed and illustrated with reference to particular applications, the principles involved are susceptible of numerous other applications which will be apparent to persons skilled in the art. For example, the translating means instead of being conductive strips and brushes, may be apertures and photoelectric means of the type utilized in position input converters or may be coded magnetic material and sensing heads. Because of this, the brushes included in the invention do not necessarily have to engage their associated tracks. As another example, the invention can be used in converting from any first digital radix to any second digital radix different from the first digital radix. In the embodiment shown in the drawings and described above, the first digital radix is binary and the second digital radix is decimal. It is evident, therefore, that various modifications are possible without departing from the spirit and scope of this invention. The invention is, therefore, to be limited only as indicated by the scope of the appended claims.

I claim:

1. A translating device for converting numerical digits on radix "two" to digits of equal value on a different radix comprising

a commutator having

angularly separated groups of conductors adapted to be selectively energized to register input digits on radix "two";

each of said groups including a plurality of angularly spaced conductive elements corresponding in number to the value of the input digit expressed on another radix,

means for successively scanning said elements, and means controlled by said scanning means for emitting electrical impulses equal in number to the value of the input digits expressed on said other radix.

2. A translating device according to claim 1 in which each of said groups includes a plurality of radially spaced rows of angularly spaced conductive elements; each row being of the same ordinal significance with respect to the input digit but of different ordinal significance with respect to the output.
